[57] **ABSTRACT**

A separable self-securing article holding device embodying an improvement which comprises a flexible wall supported layer and a rigid article holding layer, said layers being connected by welds having very substantial shear strength and having tear strength such that said welds may be readily broken by a direct sharp pull in the direction of the axes of said welds to permit direct access to said flexible layer to peel the same away from a supporting wall without damage to the surface thereof.

FIG. 6

SEPARABLE SELF-SECURING HOLDING DEVICE

BACKGROUND AND SUMMARY OF THE INVENTION

The invention herein relates to a separable self-securing article holding device adapted to be secured to a wall surface and which combines with substantial holding capacity ease of removal from a supporting wall without damage to the surface thereof.

It is desirable to have an article holding device which may be secured to a wall surface which is covered as with wall paper or other damageable coating material and from which said device may readily be removed without damage to such coating material.

There is likelihood that when a rigid device is removably secured to a damageable wall surface as by an adhesive that upon its removal it will tear or rupture its underlying or supporting surface. It has been found, however, that if a holding device is secured to a surface such as above indicated, that if such a device is sufficiently flexible it may be removed by being peeled off such a surface as by being gently rolled up for removal, that the underlying or supporting surface will avoid being damaged.

It is an object of this invention, therefore, to provide a self-securing article holding device having substantial holding capacity and having such structure that it may be removed from a supporting wall surface without damage to such surface.

It is another object of this invention to provide a self-securing article holding device having substantial shear strength and having limited tear strength.

It is still another object of this invention in view of the object above set forth to provide a holding device having a rigid load or article supporting layer and a relatively flexible layer secured to a supporting wall surface.

It is another object of this invention in view of the object above set forth to have an outer rigid article supporting layer readily removable from an underlying relatively flexible wall supported layer.

More specifically, it is an object of this invention to provide a separable self-securing article holding device comprising a flexible layer and a rigid layer, said layers being secured together by spaced welds, said flexible layer being self-securing to a supporting wall surface and said rigid layer being arranged to support an article, said welds having substantial shear strength and limited tear strength whereby said rigid layer is readily removed from said flexible layer by a sharp pull in the direction of the axes of said welds and said flexible layer may be peeled gently away from said supporting surface.

These and other objects and advantages of the invention will be set forth in the following description made in connection with the accompanying drawings in which like reference characters refer to similar parts throughout the several views and in which:

FIG. 1 is a broken view showing the device in front elevation in operating position;

FIG. 2 is an enlarged view in vertical section taken on line 2—2 of FIG. 1 as indicated;

FIG. 3 is a top plan view having layered portions thereof broken away;

FIG. 4 is a partially exploded view in vertical section on an enlarged scale showing a step in the removal of the device herein;

FIG. 5 is a view in perspective showing a modification;

FIG. 6 is a view in vertical section taken on line 6—6 of FIG. 5 as indicated; and

FIG. 7 is a broken view in perspective showing the modified device in operating position.

10 DESCRIPTION OF A PREFERRED EMBODIMENT

Referring to FIGS. 1—4, a preferred embodiment is shown of the separable self-securing article holding device herein which is indicated generally by the reference numeral 10.

Said device comprises a body portion 12 having one relatively rigid article holding outer layer 13 preferably made of polyvinyl chloride which has been found to be a very appropriate material. Said layer is referred to as 20 the forward layer. A rearward wall supported layer 16 overlies the same and is formed of flexible polyvinyl chloride and has a depending portion 16a extending somewhat below the lower edge of said layer 13.

Said layers 13 and 16 have non-adherent adjacent or 25 facing surfaces 14 and 17. Said surfaces may be treated as by being embossed to be non-adherent but in the present embodiment a plurality of thin sheets 19 of non-adherent material such as of Mylar are shown disposed between said layers.

Said layers 13 and 16 are secured together by welds 30 23 which extend through corresponding openings 19a in said sheets 19. Said welds are spaced inwardly of the peripheries or edge portions of said layers. The specific number of welds is a matter of design. Said layers 13 and 16 are directly bonded or fused by said welds and 35 said sheets 19 are free from attachment either to said layers or to one another.

Overlying the outer surface 15 of the layer 16 is an 40 appropriate adhesive 24 by means of which said layer becomes self-securing or self-holding as to a supporting surface. Overlying said adhesive layer is a protective removable cover strip 27 such as is in common use.

Carried by said layer 13 is a hook member 25 having its shank portion 25a embedded within said layer 13 as shown and having an appropriate outer projecting portion 25b by means of which articles may be supported.

As will be further described, said welds do not have great tear strength or in otherwords do not have great 45 resistance to being ruptured or torn apart by a sharp pull in the direction of the axes of the welds. However, said welds do have considerable shear strength. An article suspended from or carried by said hook 25 will exert a pull which will be distributed throughout the entire layer 13 and the pull on said layer is in a direction substantially parallel to the plane of said layer and in a direction substantially normal to the axes of said welds. In FIG. 1, the device is shown in operating position mounted onto or secured to a supporting surface 28.

Two significant benefits result from the particular 50 layer arrangement of the device herein. One benefit is that a relatively small holding device is capable of supporting an article of substantial weight. The rigid layer 13 directly bears the weight of the article spreading its load over all of the weld points. Said weld points in 55 being spaced inwardly and away from the edge portions of the layers 13 and 16, distribute said load onto the layer 16 without exerting any significant pull at the

edge portions of said layer. Thus, a maximum holding effect is obtained by the avoidance of the effect of peel back with reference to said layer.

The other significant benefit results from the character of the layer 16 and its relationship to the rigid layer 13. If the layer 16 were rigid, upon being removed from a supporting surface, said layer would exert substantial tear force upon such surface and could very readily result in damage to said surface particularly if the same were a papered or painted surface. Here, however, the outer rigid layer 13 can be readily separated from the rearward flexible layer 16 by a direct sharp pull outwardly in the direction of the axes of said welds to break said welds. The rearward or flexible layer will remain and it may be peeled away very gently from the supporting surface and this may be accomplished with very little tear force. Thus, the device herein may be secured as to a papered surface and may be removed therefrom without damage to such surface.

20

MODIFICATION

Referring to FIGS. 5-7, a modification 29 is shown of the device herein.

Said modified form comprises a flexible layer 30 and a relatively rigid layer 32 which overlie one another 25 having their adjacent surface portions non-adherent by having interposed therebetween a plurality of layers 34 of thin sheet material such as Mylar which will represent non-adherent layers. Said layers 30 and 32 will be secured to one another by said welds 38 which will extend through corresponding openings in the intervening or interposed layers 34. Said welds will be spaced apart and will be spaced inwardly of the edge portions of said layers 30 and 32.

Applied to each of the outer remote surface portions 35 31 and 33 of said layers is a suitable adhesive 37 and overlying the same are removable protective cover strips 39 and 40.

With the cover strip 40 removed from the surface portion 33, an article 43 shown here as a small shelf is 40 secured to said surface. The cover strip 39 is removed from the surface portion 31 and said exposed surface is then applied to a supporting wall 28 under suitable pressure.

As above described, any object placed upon said 45 shelf 43 will exert predominantly a shear force. For removal of the device from the supporting surface, an outward pull of said shelf will break the welds 38 leaving the relatively flexible layer 30 secured to the supporting wall. As above described, said layer 30 is re- 50

moved by being peeled gently away from said surface with no resulting damage to said surface.

The device in the forms here described have performed very successfully in actual use in the manner as indicated.

It will of course be understood that various changes may be made in form, details, arrangement and proportions of the parts without departing from the scope of the invention herein which, generally stated, consists in 10 an apparatus capable of carrying out the objects above set forth, in the parts and combinations of parts disclosed and defined in the appended claims.

What is claimed is:

1. A separable self-securing article holding device, 15 having in combination
a body portion comprising a pair of layers,
one of said layers being rigid,
and other of said layers being flexible,
said layers being separably connected by a plurality of
spaced-apart welds spaced inwardly of the peripheries
of said layers,
said welds being arranged and constructed to with-
stand considerable shear force and to separate
under relatively small tear force,
said flexible layer having an adhesive outer surface
layer, and
article holding means carried by said rigid layer, said
rigid layer distributing the load carried by it over
said welds without exerting any significant pull at
the edge portions of said flexible layer.

2. A separable self-securing article holding device, 30 having in combination

a body portion comprising a pair of layers,
means rendering selected areas of the adjacent sur-
faces of said layers non-adherent,
one of said layers being rigid,
the other of said layers being flexible,
means forming spaced-apart welds connecting said
layers inwardly of the peripheries thereof,
said welds being arranged and constructed to have
considerable shear strength and to have very little
tear strength,
said flexible layer having an adhesive outer surface
layer, and
article holding means carried by said rigid layer, said
rigid layer distributing its load throughout the
welds connecting it and said flexible layer and thus
avoiding the effect of peel back at the periphery of
said flexible layer.
